UNITED STATES PATENT OFFICE.

ROBERT HOPE-JONES, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK.

TRACKER FOR AUTOMATIC MUSICAL INSTRUMENTS.

1,070,471.

Specification of Letters Patent. Patented Aug. 19, 1913.

Application filed September 7, 1911. Serial No. 648,145.

To all whom it may concern:

Be it known that I, ROBERT HOPE-JONES, a subject of the King of England, residing at North Tonawanda, in the county of 5 Niagara and State of New York, have invented new and useful Improvements in Trackers for Automatic Musical Instruments, of which the following is a specification.

10 In orchestrions, organs and other musical instruments in which the so-called "stops" and expression devices as well as the sound producing parts are controlled by a perforate music sheet, a comparatively large 15 number of additional perforations and tracker ducts are required according to the number of stops embraced by the instrument. It is well known that a single music sheet wide enough to accommodate the 20 requisite large number of perforations is impracticable, owing to its correspondingly increased liability to warp, expand or shrink under atmospheric changes. To overcome this difficulty it has been proposed to employ 25 a plurality of narrow music sheets driven to travel synchronously, but this construction has also proved unsatisfactory, largely on account of the high degree of accuracy in the construction of the driving 30 mechanism required in order to secure an absolutely synchronous movement of the several music sheets.

It is the object of my invention to so construct the tracker and its coöperating mechanism that several movements may be obtained from a single transverse space of the tracker, thus multiplying its capacity without correspondingly increasing its length and permitting the use of a single comparatively narrow music sheet which is no more liable to shrink or warp than ordinary sheets.

In the accompanying drawings consisting of 3 sheets: Figure 1 is a transverse section of the improved tracker combined with a diagrammatic view of the apparatus co-operating therewith. Fig. 2 is an enlarged vertical section of one of the relays or electro-pneumatics. Fig. 3 is a similar section 40 of one of the electro-pneumatic stop-controlling devices. Fig. 4 is a fragmentary plan view of the music sheet. Fig. 5 is a face view of the tracker. Figs. 6, 7, 8, 9 and 50 10 are fragmentary plan views of the music

sheet and tracker, showing different perforations of the sheet in operative relation to the corresponding ducts of the tracker. Fig. 11 is a diagrammatic view showing a modified construction of the apparatus. Fig. 12 is a fragmentary plan view of the 60 music sheet and tracker of said modification.

Similar characters of reference indicate corresponding parts throughout the several views.

A indicates the tracker or tracker-board having the customary single or ordinary ducts *a*, for controlling the sound-producing parts, these ducts forming no part of the present invention. In addition to such ordinary ducts, the tracker is provided with one or more transverse rows of ducts *b*, *b*¹, *b*², *b*³, *b*⁴ for automatically operating or controlling the stops, expression devices, coin-controlled devices or other parts of a 75 musical instrument or other apparatus. Each of such transverse rows or spaces may comprise two or more ducts arranged in alinement with each other, so as to be successively passed over by correspondingly 80 alined perforations or slots *c*, *c*¹, *c*², *c*³, *c*⁴ of the music sheet *C*. These ducts have substantially the same extent or area cross-wise of the tracker, as shown. In the construction shown in Figs. 1-10 of the drawings, there are five ducts in each transverse row but a greater or less number may be employed, if desired. These ducts are connected by independent tubes or conduits *d* with relays or pneumatics *D*-*D*⁴. Those 90 shown in the drawings by way of example are electro-pneumatic or pneumato-electric and each comprises a box or chest divided by a flexible diaphragm *e* of leather or other suitable material, into an upper suction 95 chamber *e*¹ and a lower air or atmospheric chamber *e*². The upper chamber is permanently connected by a passage *e*³ with a suction bellows or other suitable exhaust device, not shown in the drawings, while the lower chamber is connected with the corresponding tracker duct by the tube *d* and also with the upper chamber *e*¹ by a "bleed" or small passage *e*⁴. Applied to the upper side of this diaphragm is a thin metallic 105 spring or switch member *f* which has a tendency to move downward into contact with a contact-pin or screw *f*¹ extending up-

wardly through the bottom of the chamber e^2 , the diaphragm being perforated under the spring to permit such contact. Extending into the suction chamber e^1 opposite the contact-screw f^1 is a similar contact pin or screw f^2 with which the spring is adapted to contact when the diaphragm is raised to the position shown by dotted lines in Fig. 1. So long as the tracker ducts $b-b^4$ are covered by the music sheet, the spring f will press the diaphragm downward and bear against the lower contact-screw f^1 . As soon, however, as a duct is uncovered, atmospheric air will pass through it and the corresponding tube d , enter the lower chamber e^2 and raise the diaphragm, pressing the spring upward into contact with the upper contact-screw f^2 .

The electro-pneumatics or relays $D-D^4$ govern a corresponding number of controllers or controlling mechanisms $G-G^4$ which in turn cause or control the operation of organ-stops, expression devices or other desired parts or mechanisms, not shown in the drawings. The controlling devices shown in the drawings are of the electro-pneumatic type, and as shown in Fig. 3, each comprises a chest or case containing a pressure chamber g which is connected by a passage g^1 with a bellows or other source of air pressure, not shown in the drawings.

g^2 indicates the pressure outlet or conduit of the chamber g which leads from a valve chamber h connected with said chamber by a port h^1 controlled by a valve h^2 the latter also controlling an exhaust port h^3 of chamber h . This valve is in turn controlled by a pneumatic h^4 arranged within the chamber g and having its movable board connected with the stem of said valve. This pneumatic is carried by a fixed block h^4 containing an exhaust passage h^5 which connects the pneumatic with a valve chamber h^6 having an exhaust port h^7 leading to the outer atmosphere. This port h^7 is normally closed by a valve i consisting of or carried by the armature of an electro-magnet I arranged in the block h^4 . The valve chamber h^6 is connected with the pressure chamber g by a port i^1 which is closed by the valve i when the magnet I is energized.

In the normal condition of the controlling device just described, the exhaust port h^7 is closed by the valve i and the pressure port i^1 is open, thus equalizing the pressure on the inner and outer sides of the pneumatic h^4 , allowing the pressure supply valve h^2 to remain closed and cutting off the motive pressure from the outlet conduit g^2 and any mechanism connected therewith. When the magnet I is energized, the armature-valve i is attracted, closing the pressure port i^1 and opening the exhaust port h^7 . The pressure is now allowed to exhaust from the pneumatic h^4 which is collapsed by the pressure

in the chamber g , opening the pressure-supply valve h and admitting pressure to the conduit g^2 and the part or mechanism to be actuated. This mechanism which is not shown in the drawings, may consist of a pair of alternately-operating motor pneumatics connected with the slide of an organ stop in such manner that one motor pneumatic shifts the slide in one direction or "on", and the other shifts it in the opposite direction or "off".

Referring to Fig. 1, K indicates a battery or other electric generator, k a conductor or lead from its negative pole and k^1 the lead from the positive pole, which latter is connected with the contact-spring f of the last relay D^4 of the series. The upper contact-screw f^2 of the first relay D is connected with the negative lead k by a conductor 1 which includes the electro-magnet I of the corresponding controller G^4 . The lower contact-screws f^1 of the four relays D , D^1 , D^2 and D^3 are connected with said negative lead by conductors or branches 2, 3, 4 and 5, respectively, which include the electro-magnets I of the corresponding controllers G^3 , G^2 , G^1 and G . A wire 6 connects the spring f of the first relay D with the upper contact-screw f^2 of the second relay D^1 ; a wire 7 connects the spring of the second relay D^1 with the upper contact-screw of the third relay D^2 , and a wire 8 likewise connects the spring of the third relay with the upper contact-screw of the fourth relay D^3 .

9 and 10 indicate a pair of switch contacts carried by a support 11 and adapted to be connected by a suitable switch 12 in the normal condition of the apparatus. The contact 9 is connected by a wire 13 with the contact-spring f of the fourth relay D^4 ; 105 while the other switch contact 10 is connected by a wire 14 with the upper contact-screw f^2 of the last relay D^4 . The lower contact-screw f^1 of the last-mentioned relay is connected with the negative pole of the battery K by a wire 15 containing a circuit-closing electro-magnet 16 arranged to move the switch 12 into the closed position shown in the drawings. So long as the spring f of the last relay D^4 remains in its depressed position, the circuit which includes the magnet 16 is closed through the battery K , wire 15, lower contact-screw f^1 of said relay, its spring f and the wire 14, energizing said magnet and holding the switch 12 in its closed position.

As hereinafter more fully described, it is necessary to break the main circuit after operating an organ-stop or other piece of mechanism to avoid premature or other improper actuation of other stops or mechanisms controlled by the same transverse series of tracker ducts. For this purpose, a switch-opening electro-magnet 17 is employed which is adapted to withdraw the switch 12

from the switch-contacts 9 and 10, so as to disconnect them. This closing magnet is included in a supplemental circuit comprising parallel conductors 18 and 19, respectively connected with the poles of the battery K. Connected with the pressure outlet g^2 of each controller G—G⁴ is a switch pneumatic L which is normally collapsed by a spring l and inflated by the air pressure when the corresponding valve h^2 is opened. The movable board of each pneumatic L carries a switch or switch plate l¹ which in the inflated condition of the pneumatic contacts with and connects a pair of switch-contacts or terminals 20 and 21 connected with the conductors 18 and 19. Normally, the circuit of the switch-opening magnet 17 is broken, but whenever one of the switch-pneumatics L is inflated, said circuit is closed, energizing said magnet and causing it to open the switch 12.

The perforations C—C⁴ of the music sheet are of different lengths so as to register with one or more of the transverse tracker ducts of each row, each size or length controlling one of the several controllers G—G⁴. The perforation e is adapted to coöperate with the last or fifth tracker duct b⁴ and is just large enough to register with that duct only, as shown in Fig. 6; the next perforation or slot c¹ is adapted to coöperate only with the fourth and fifth ducts b³ and b⁴, being of the proper length to register simultaneously with the same, as shown in Fig. 7, and so on, the slot c² being long enough to bridge the three ducts b², b³, b⁴, as seen in Fig. 8, the slot c³ longer to bridge the four ducts b¹—b⁴ (Fig. 9), and the slot c⁴ still longer to bridge all of the ducts (Fig. 10).

The operation of the apparatus is as follows: It may be generally stated that it is the opening of the last tracker duct b¹ which in every case causes the cutting in of the battery K or other source of motive energy; and the selection of the organ-stop or other piece of mechanism to be operated is determined by the state of the duct or ducts immediately preceding the last duct, *i. e.* whether one or more of such preceding ducts are covered or uncovered. When one of the smallest or single-duct perforation e comes into register with the last duct b⁴, the controller G is actuated; when a two-duct slot c¹ registers with the ducts b³—b⁴, the controller G¹ is operated; when a three-duct slot c² registers with the ducts b², b³ and b⁴ the controller G² is operated, and so on with the progressively longer slots c³ and c⁴ and the corresponding controllers G³ and G⁴. It will be noted that the contact-spring f of the last relay D⁴ is permanently connected with the positive pole of the battery K, and that in the normal condition of the apparatus, the magnet-circuits of the several controllers

G—G⁴ are broken at the upper contact-screws f² of the several relays. It will be further noted that even when the diaphragm of any of the relays, except the last one D⁴, is raised, no controller-actuating circuit is established, the circuit in that case being broken at the upper contact-screw f² of the relay next below. Following the action of one of the single-duct holes or perforations c and assuming the music sheet to travel in the direction of the arrow, as this hole passes over the first tracker duct b, the diaphragm e and spring f of the corresponding relay D are momentarily raised to the dotted position shown in Fig. 1, but are allowed to drop again after the hole passes on to the tracker-duct b¹, leaving the controllers G—G⁴ uninfluenced. The diaphragm and contact-spring of relay D¹ are now likewise raised but fall again when the hole leaves duct b¹. The same action takes place in relays D² and D³ when the hole passes over the tracker ducts b² and b³, but when the hole registers with the last duct b⁴, the resulting elevation of the spring f of the last relay D⁴ into contact with the corresponding screw f² switches the battery K into circuit with the magnet I of the controller G, depressing the exhaust valve i and opening the exhaust port h¹. The pneumatic h² is thereby collapsed and opens the pressure valve h², supplying motive fluid for operating the slide of the organ stop or other part to be actuated. When the spring of the relay D⁴ is thus raised, current flows from the positive pole of the battery through wire K¹, raised spring f of relay D⁴, upper contact screw f² of the latter, wire 14, switch 12, wire 13, depressed spring of relay D³, lower contact screw f¹ of the latter, magnet I of controller G and wires 5 and h to the negative pole of the battery. None of the remaining controllers G¹—G⁴ are affected by this action, inasmuch as their magnet-circuits remain broken at the corresponding relays by the depression of their contact-springs f.

Simultaneously with the operation of the organ-stop or other actuated part, motive pressure is admitted to the switch-pneumatic L of the controller G, causing its switch l to rise and connect the corresponding contacts 20 and 21 and closing the circuit of the switch-opening magnet 17. The latter now withdraws the main switch 12 from the contacts 9 and 10, breaking the main or motive circuit and preventing the further operation of the whole apparatus until the operative perforation of the music sheet leaves the last tracker duct b⁴, whereupon the raised diaphragm of the relay D⁴ drops to its former position, breaking the magnet-circuit of the controller G. The exhaust valve i of said controller is now raised by the pressure in the chamber g and pressure

is again admitted to the valve-actuating pneumatic h^3 , which thereupon expands and closes the valve h^2 and cuts off the further supply of pressure to the conduit g^2 , leaving the actuated part or mechanism in its shifted position. The pressure is at the same time cut off from the switch-pneumatic L , which is now collapsed by the spring l , opening the corresponding supplemental switch l^1 and breaking the circuit of the switch-opening magnet 17. The return of the spring of the relay D^4 into contact with the corresponding lower screw f^1 again closes the circuit in which the battery and the closing magnet 16 of the main switch 12 are included, and said switch is therefore closed by the magnet 16 immediately after the opening magnet 17 is deenergized, thus reestablishing said normally-closed circuit, preparatory to the next operation of the apparatus. Assuming now that a double or two-duct slot c^1 of the music sheet passes over the tracker, the diaphragms of the relays D , D^1 and D^2 will idly rise and fall, as hereinbefore described with reference to the action of a one-duct perforation, but as soon as said double-duct registers simultaneously with the last duct b^4 and the second last duct b^3 , as shown in Fig. 7, the diaphragms of both relays D^3 and D^4 are raised and their springs moved into contact with the upper screws f^2 thereof, as shown by dotted lines in Fig. 1. Current will now flow from positive pole of the battery through the wire h^1 , raised contact spring f of the relay D^4 , upper contact screw f^2 of the latter, wire 14, switch 12, wire 13, raised contact spring of relay D^3 , upper contact screw of the latter, wire 8, depressed contact spring of relay D^2 , lower contact screw of the latter, the magnet of controller G^1 and wires 4 and h to the negative pole of the battery. The controller G^1 is thus operated and caused to admit the motive pressure to the stop or other part connected therewith. When the slot c^1 leaves the last tracker duct b^4 , the main circuit is broken and again reestablished as hereinbefore described.

When a three-duct slot c^2 passes over the tracker, all the controllers remain in their inactive position until the slot registers simultaneously with the last tracker duct b^4 and the two immediately preceding ones b^3 , b^2 , as shown in Fig. 8. As soon as this occurs, the diaphragms of the three relays D^2 , D^3 and D^4 are raised and their springs brought in contact with the upper contact screws thereof. Current then flows from the positive pole of the battery through the relay D^4 , main switch 12, relay D^3 , wire 8, raised contact spring of relay D^2 , upper contact screw of the latter, wire 7, depressed contact spring of relay D^1 , lower contact screw of the latter, magnet of controller G^2

and wires 3 and h back to the battery, as before described with reference to the two-duct slot c^1 , thus actuating the controller G^2 and the stop or other part governed thereby. In like manner, controller G^3 is actuated when a four-duct slot c^3 registers simultaneously with the ducts b , b^1 , b^2 and b^3 , as shown in Fig. 9, and the controller G^4 is operated when a five-duct slot c^4 registers simultaneously with all of the ducts b — b^4 , as shown in Fig. 10. The necessity of automatically breaking the main circuit immediately after the operation of one of the controllers G — G^4 will now be apparent. In the absence of that provision those slots or perforations of the music sheet which are long enough to simultaneously register with two or more tracker ducts would obviously actuate one or more controllers in addition to the particular one intended to be operated, because a slot of a given length would necessarily include and repeat the action of shorter slots. For example, a five-duct slot c^4 would not only operate the corresponding controller G^4 , but by its continued travel across the tracker would act successively as a four, three, two and single-duct perforation, and thus operate all of the controllers and defeat the purpose of the apparatus.

In the practical use of the apparatus, the music sheet is provided with two sets of such graduated stop-controlling perforations c — c^4 , one set for throwing stops "on" and the other for throwing them "off."

In the modified construction shown in Figs. 11 and 12, the main switch 12^a is operated pneumatically instead of electrically, dispensing with the magnets 16 and 17 and the corresponding switch pneumatics L of the first-described apparatus. In this case, the switch 12^a is connected with a motor pneumatic M which is controlled by an auxiliary duct b^5 of the tracker through the medium of a suitable pneumatic action N such for instance as commonly employed in pneumatic pianos. The auxiliary duct b^5 is arranged at the rear end of the series of stop-controlling ducts b — b^4 , so that as soon as a one-duct perforation c of the music sheet or the front end of an elongated perforation registers with said auxiliary duct the switch-pneumatic M is collapsed and the switch opened, the latter being again closed by a return spring n as soon as said perforation passes the auxiliary duct.

I do not wish to be limited to the particular construction of the relays, controllers, switches and other parts herein shown and described, as they may obviously be modified without departing from the invention.

I claim as my invention:

1. The combination of a tracker having a plurality of ducts arranged in line transversely thereof, a series of pneumatics co-operating with the respective tracker-ducts,

controlling mechanisms for the parts to be actuated governed by said pneumatics, a source of energy, means controlled by the last of said series of pneumatics for bringing one or another of said controlling mechanisms under the influence of said source of energy, and a perforated sheet coöperating with the tracker and having a plurality of perforations of different lengths adapted to uncover a greater or less number of said ducts simultaneously.

2. The combination of a tracker having a plurality of ducts arranged in line transversely thereof, said several ducts having substantially the same extent transversely of the tracker, a series of pneumatics coöperating with the respective tracker ducts, controlling mechanisms for the parts to be actuated governed by said pneumatics, a source of energy, means controlled by the last of said series of pneumatics for bringing one or another of said controlling mechanisms under the influence of said source of energy, and a perforated sheet coöperating with the tracker and having a plurality of perforations of different lengths adapted to uncover a greater or less number of said ducts simultaneously.

3. The combination of a tracker having a plurality of ducts arranged in line transversely thereof, one or more of said ducts adapted to be uncovered simultaneously by a music sheet having corresponding perforations of different lengths, a series of pneumatics coöperating with the respective tracker-ducts, controlling mechanisms for the parts to be actuated governed by said pneumatics, a source of energy, and means controlled by the last of said series of pneumatics for bringing one or another of said controlling mechanisms under the influence of said source of energy.

4. The combination of a tracker having a series of ducts arranged transversely thereof, a series of pneumato electric relays respectively connected with said ducts, a main circuit including an electric generator, the last relay of the series having a contact and a pneumatically-operated switch member coöperating therewith, the first relay and the intermediate relay or relays each having opposing contacts and an interposed pneumatically-operated switch-member coöperating therewith, the contacts and switch members of successive relays being serially connected together, except the initial contact of the first relay and the final or switch-member of the last relay, said last-named initial and final contact-elements being respectively connected with the poles of said generator, electric connections leading from one side of said generator to contacts of said relays, and electro-magnetic controlling mechanisms arranged in said connections.

5. The combination of a tracker having a

series of ducts arranged transversely thereof, a series of pneumato-electric relays respectively connected with said ducts, a main circuit including an electric generator, the last relay of the series having a contact and a pneumatically-operated switch member coöperating therewith, the first relay and the intermediate relay or relays each having opposing contacts and an interposed pneumatically operated switch-member coöperating therewith, the contacts and switch members of successive relays being serially connected together, except the initial contact of the first relay and the final or switch member of the last relay, said last-named initial and final contact-elements being respectively connected with the poles of said generator, electric connections leading from one side of said generator to contacts of said relays, electro-magnetic controlling mechanisms arranged in said connections, and means for automatically breaking said main circuit immediately after the operation of one of said controlling devices.

6. The combination of a tracker having a plurality of ducts arranged in line transversely thereof, an electric circuit including a generator, a series of electro-pneumatics coöperating with the respective tracker-ducts, the last of the series of pneumatics including a contact and a coöperating switch member connected with one pole of said generator, each of the remaining pneumatics having opposing upper and lower contacts and an interposed switch-member coöperating therewith, the upper contact of the first pneumatic being connected by a lead with the other pole of the generator, an electro-magnetic controlling device for a part to be actuated arranged in said lead, and branches extending from said lead to the lower contacts of the respective electro-pneumatics and containing similar electro-magnetic controlling devices, the switch member of each pneumatic, except the last one, being connected with the upper contact of the next succeeding pneumatic.

7. The combination of a tracker having a plurality of ducts arranged in line transversely thereof, an electric circuit including a generator, a series of electro-pneumatics coöperating with the respective tracker-ducts, the last of the series of pneumatics including a contact and a coöperating switch member connected with one pole of said generator, each of the remaining pneumatics having opposing upper and lower contacts and an interposed switch-member coöperating therewith, said switch members contacting normally with the corresponding lower contacts, the upper contact of the first pneumatic being connected by a lead with the other pole of the generator, an electro-magnetic controlling device for a part to be actuated arranged in said lead, and branches ex-

- tending from said lead to the lower contacts of the respective electro-pneumatics and containing similar electro-magnetic controlling devices, the switch member of each 5 pneumatic, except the last one, being connected with the upper contact of the next succeeding pneumatic.
8. The combination of a tracker having a plurality of ducts arranged in line transversely thereof, an electric circuit including 10 a generator, a series of electro-pneumatics coöperating with the respective tracker-ducts, the last of the series of pneumatics including a contact and a coöperating 15 switch member connected with one pole of said generator, each of the remaining pneumatics having opposing upper and lower contacts and an interposed switch-member coöperating therewith, the upper contact of 20 the first pneumatic being connected by a lead with the other pole of the generator, an electro-magnetic controlling device for a part to be actuated arranged in said lead, branches extending from said lead to the 25 lower contacts of the respective electro-pneumatics and containing similar electro-magnetic controlling devices, the switch member of each pneumatic, except the last one, being connected with the upper contact 30 of the next succeeding pneumatic, and means for automatically breaking said circuit immediately after the operation of one of said controlling devices.
9. The combination of a tracker having a plurality of perforations arranged in line 35 transversely thereof, a main electric circuit, a series of electro-pneumatics connected with the respective tracker ducts, electro-magnetic controlling devices controlled by said pneumatics, a normally-closed switch in said 40 circuit, a supplemental circuit containing a magnet arranged to open said switch, and means governed by said controlling devices for closing said supplemental circuit.
10. The combination of a tracker having a 45 plurality of perforations arranged in line transversely thereof, a main electric circuit, a series of electro-pneumatics coöperating with the respective tracker ducts, electro-pneumatic controlling devices controlled by 50 said pneumatics, a normally-closed switch in said circuit, a supplemental circuit containing a magnet arranged to open said switch, said supplemental circuit having a 55 pair of contact-terminals associated with each of said controlling devices, switch-members coöperating with said terminals, and switch-pneumatics connected with the respective controlling devices and actuating said switch members. 60
